UNITED STATES PATENT OFFICE.

RICHARD H. MATHER, OF WINDSOR, CONNECTICUT.

ARC LIGHT.

SPECIFICATION forming part of Letters Patent No. 446,109, dated February 10, 1891.

Application filed October 11, 1886. Renewed October 27, 1890. Serial No. 369,398. (No model.)

To all whom it may concern:

Be it known that I, RICHARD H. MATHER, of Windsor, in Hartford county, Connecticut, have invented certain new and useful Improvements in Electric-Arc Lamps, which are described in the following specification and illustrated by the accompanying drawings.

This invention includes a feeding device for the carbons of an electric-arc lamp, and comprises a reversible electric motor, a compound switch which controls said motor, and intermediate mechanism whereby positive motion is transmitted from said motor to one of said carbons.

The best mode in which I have contemplated the application of the principle of my invention is shown in said drawings, in which—

Figure 1 is a vertical section of my improved lamp. Fig. 2 is a top view of the same, the cap being removed. Figs. 3 to 7, inclusive, are details. Fig. 8 is a diagram showing the course of current through the various parts of the lamp.

In the views, the numeral 1 denotes a cast-iron cylindrical box having ears 2 and 2, by which the box and dependent lamp may be suspended in the position shown in Fig. 1. This box is provided with binding-posts 3 and 4, which are the positive and negative terminals of the lamp, respectively, and with a removable cap 5, which covers the otherwise open top of the box. Projecting outward and downward from box 1 and skirting its solid floor or bottom 6 is an annular flange 7, which externally presents the form of a frustum of a cone. This box is also provided with two bosses 8 and 8, which project and open downward from floor 6 within flange 7. Within this box is an electric motor, which is preferably of the general description exhibited in my application, No. 200,929, for a patent upon an electro-mechanical movement filed May 3, 1886. The field-magnet of this motor comprises two limbs, which are wound as an electro-magnet in the usual manner with helices 9 and 10, respectively, and two pole-pieces, which are adjacent to armature 11. The latter is mounted in the usual manner upon a shaft which is journaled in said field-magnet and in a yoke 12, which is bolted thereto. The commutator 13 is mounted upon

said shaft in the usual manner between the limbs of the field-magnet aforesaid. Brushes 14 and 15, which allow commutator 13 to rotate in either direction, are held in proper positions of contact therewith by their respective brush-holders 16 and 17, which are bolted to opposite sides of said field-magnet, but are insulated therefrom. Said armature-shaft terminates in a worm 18. This motor may be attached to floor 6 by screws, as shown in Fig. 1. Within the same box 1 and similarly attached to floor 6 is a switch, which is shown in Fig. 4 in a central vertical section on a broken line in Fig. 2. This switch comprises an electro-magnet of solenoid form, having helices 19 and 20, which are wound in one and the same direction. The cylindrical core 21 of this magnet is armed at the top with a projecting insulated copper contact-plate 22 and is perforated by a transverse slot 23. Two insulated strips of copper 24 and 25 are mounted upon the switch-magnet within reach of plate 22 and upon opposite sides of the same. A third insulated strip of copper 26 is similarly mounted just below copper 25. A lever 27, which is centrally pivoted in a standard rising from the top of the switch-magnet, enters slots 23, and being provided with a terminal spring 28 tends to lift core 21. Similarly attached in box 1 is a similar solenoid electro-magnet 29, which is shown in Fig. 3 as a central vertical section upon a broken line of Fig. 2. This magnet has a single helix 30 and a cylindrical core 31, which is perforated by a transverse slot 32, and is armed at the top with a projecting insulated copper contact-plate 33. Upon magnet 29, just above and within reach of plate 33, is mounted an insulated strip of copper 34. A lever 35, which is centrally pivoted in a standard rising from the top of magnet 29, is provided with a spring 36, which tends to lift core 31. One end of this lever passes through slot 32, while the other end of the same forks laterally in two branches, between which is pivoted collar 37. In the same box is the upper portion of the feeding-rod 38, which is a straight bar of brass passing loosely through collar 37 and provided with a terminal fixed collar or stop 39. This rod is journaled in the two arms of a double standard 40, which is attached by screws to

the field-magnet of said electric motor. A worm-wheel 41, having a slotted hub 42, is mounted loosely upon rod 38 between the arms of standard 40 in a position of constant engagement with worm 18. A pin 43, projecting radially from rod 38, is adapted to travel from end to end of the slot in hub 42. The electrical continuity of rod 38 is interrupted by an insulating joint 44, which is shown in longitudinal section in Fig. 5. This joint is preferably constructed in the manner exhibited in David Williamson's application, Serial No. 195,797, for a patent on insulating-joints, filed March 19, 1886. According to that manner of construction said rod is divided into two portions, one of which is armed with a fixed terminal collar 46, while the other is reduced to the form of a tongue 45, which is provided with a terminal screw-thread. This tongue passes through collar 46 and is separated therefrom by an indefinite number of mica disks or washers and by an intermediate cylindrical air-chamber 49. By means of nut 47 said washers are clamped together upon tongue 45 in two groups 48, each of which is partly countersunk in said collar. A copper brush 50, mounted upon a brass standard 51, which rises from floor 6, encounters rod 38 below joint 44.

Box 1, whose contents have now been described, constitutes a portion of the frame of the lamp. The remaining portion of the frame consists of two like perpendicular brass tubes 52 and a connecting-yoke 53. The upper end of each tube 52 is inserted in a boss 58 at the bottom of box 1, and is held therein by a set-screw. The lower end of each tube 52 is similarly inserted and held in one end of yoke 53. The middle part of this yoke 40 contains an insulated carbon-holder, which is shown in vertical sections in Figs. 1 and 7. This carbon-holder consists of a metallic tube 54, which is open at both ends, is provided with a stop-flange 56 at the top, and with an insulated set-screw 57, and is separated from yoke 53 by a sleeve 55, which is of similar form and of insulating material. A sliding yoke 60 is formed on tubes 52 by means of two like metallic sleeves 59 and an intermediate cross-piece 58. This cross-piece is rigidly joined to each of said sleeves, and is insulated therefrom by the use of mica washers, applied in the manner illustrated in Fig. 1. This yoke is provided with a central carbon-holder 61 for the upper carbon of the lamp. Yoke 60 is also provided with a device for effecting an engagement with the feeding-rod 38. This engaging device consists of a tubular enlargement of yoke 60 and a sliding engagement-block 62 inclosed therein. This block, which is threaded in one side as a female screw for engagement with a thread upon rod 38, is located in a recess 63 at one side of said rod, and is provided with a spring 64, which tends to produce an engagement between said block 62 and rod 38. This block is hollow and contains a cam 65,

which is pivoted in said yoke, and is provided with a finger-piece 66 and a spring 67. Cam 65 is adapted to engage a re-entrant shoulder within the hollow interior of block 62. The lower portion of rod 38 passes through a hole in floor 6, through said tubular enlargement of yoke 60, and through a hole 68 in yoke 53, and is insulated from floor 6 and yoke 53 by mica bushings. Carbons 84 and 85 are inserted in holders 61 and 86, respectively.

Such being the elements of said lamp, their electrical connections not already specified are as follows: Terminal 3 is connected by coarse wire 69 with copper 24 and by coarse wire 70 with helix 9. Brush-holder 16 is connected with helices 9 and 10 by coarse wires 71 and 72, respectively. Helix 10 is connected by coarse wire 73 with helix 30, and that helix is connected by coarse 74 wire with brush 50. Helix 10 is also connected through wire 73 and by a coarse wire 75 branching therefrom with helix 19, which is connected by coarse wire 76 with copper 34. Terminal 4 is connected with holder 86 by wire 77, and with contact-plate 33 by wire 78. Copper 25 is connected by wire 79 with wire 73. Copper 26 is connected by wire 80 with brush 50, and copper 22 by wire 81 with holder 17. Helix 20 is connected with terminals 3 and 4 by fine wires 82 and 83, respectively. By means of terminals 3 and 4 the lamp is placed in circuit with a generator in the usual manner.

This invention further presents all other features and particulars of construction which are necessarily involved in its mode of operation, which is now to be explained.

When no current is supplied to the lamp, lever 35 occupies the position shown in Fig. 3, and plates 33 and 34 are consequently in mutual contact. At the same time lever 27 is deflected to such a position that plates 22 and 24 are also held in mutual contact. If now in this position of affairs a normal current be supplied from the generator, that current passes from terminal 3 in two principal courses as follows: One portion of said current passes by wire 69 to copper 24, thence immediately to copper 22; thence by wire 81 to holder 17, thence successively through brush 15, commutator and armature 13 and 11, and brush 14 to holder 16, and thence in the course hereinafter described. A second portion of said current passes from terminal 3 through wire 70, helix 9, wire 71 to holder 16. The current so conducted in two courses to holder 16 goes thence through wire 72 and helix 10 to wire 73 and there divides into two parts, one of which goes on through helix 30, wire 74, brush 50, rod 38, yoke 60, carbons 84 and 85, and wire 77 to terminal 4, while the other part passes successively through wire 75, helix 19, wire 76, coppers 34 and 33, and wire 78 to the same terminal 4. At the same time an inappreciable part of the current which is supplied passes between said terminals by the way of wires 82 and 83 and

helix 20. This distribution of current, however, is but momentary. For the passage of current through the motor the switch-magnet and the lifting-magnet energize those devices in the following manner: The action of magnet 29 instantly causes the above-mentioned portion of current passing through helix 19 to be interrupted between plates 33 and 34. Lever 35 of magnet 29 then comes into engagement with stop-collar 30 by means of collar 37, and thereby lifts rod 38, sliding yoke 60 and carbon 84 until the latter is separated from carbon 85 by a distance which is slightly greater than their normal separation. Under the action of helix 20 of the switch-magnet copper 22 is separated from copper 24 and brought to contact with copper 25. This interrupts the current which flowed in the above-delineated course through armature 11, and allows a current to pass from holder 16, through brush 14, through armature and commutator 11 and 13 in a reverse direction, and thence successively through brush 15, holder 17, wire 81, coppers 22 and 25, and wire 79 to wire 73. Said motor acting upon rod 38, through worm 18, worm-wheel 41, slotted hub 42, and pin 43, rotates that rod in such a direction as to move yoke 60 downward, and this downward motion continues until the separation of said carbons is reduced to the normal length of the arc for which the lamp is adjusted. Through the diminished electro-magnetic efficiency of the switch-magnet the mutual contact of coppers 22 and 25 is then in turn interrupted and the motor stops. If the carbons should be at a distance from each other when the lamp is started up, the upper carbon will be carried downward as far as may be necessary, in the manner last described, and with the same result, and whenever during the operation of the lamp the carbons become unduly separated through the ordinary consumption of the same or through any other cause the consequent increase of resistance in the carbon-circuit so increases the current through helix 20 that coppers 22 and 25 are brought together again, and the motor is again brought into operation in the same manner and with same effect as before; but whenever the carbons approach too near to each other the electro-magnetic efficiency of the relay-magnet is reduced, contact is made again between coppers 22 and 24, current passes again through armature 11 in the course first above described, the motor is reversed, the upper carbon is thereby raised, and the normal separation of the carbons is thus restored. If any stoppage occurs during the operation of the lamp and the carbons consequently remain unduly separated, the energy exerted by the relay-magnet is increased, and copper 22, pressing downward with unusual force upon the top of copper 25, bends the latter to a position of contact with copper 26. The current from wire 73, through helix 30 and wire 74 to brush 50, is thus short-circuited

by the way of wire 79, coppers 25 and 26, and wire 80 to brush 50, and lifting-magnet 29 is inactive. Copper 33 consequently rises to contact with copper 34, and thus the carbon current is short-circuited through the armature and the field-magnet helices of the motor and through relay-helix 19. The relay-magnet then holds coppers 25 and 22 in mutual contact, as above described, and the carbon current remains short-circuited, as described, so long as the stoppage continues.

If through accident or heedlessness the upper carbon having run by should be found partly side by side with the lower carbon when current is supplied to the lamp, the motor will feed backward until the carbons are duly separated in the manner already described.

In this improved lamp carbons of double length can be used in a frame of ordinary dimensions. At the same time the separation and approach of the carbons are effected by a positive motion and are controlled with great delicacy and precision.

Having described the construction and operation of my invention, I now claim—

1. In an electric-arc lamp, a movable carbon-carrier, a reversible electric motor whose field-magnet is excited by two helices in series and whose armature is located in a derived circuit, and a compound switch having separate connections with said armature and with the field-magnet circuit upon opposite sides of the field-magnet, in combination with mechanism for transmitting motion from said armature to said carrier, substantially as and for the purpose specified.

2. In an electric-arc lamp, a carbon-carrying slide, a rotary electric motor whose field-magnet is excited by two helices arranged in series, a two-point switch having one of its points connected to the circuit on one side of said helices and having the other of said points connected to the circuit on the other side of said helices, and a connection from the switch to the circuit containing said helices at a point between the latter, said connection containing the armature of said motor, in combination with mechanism which is adapted to convert the rotary motion of said armature into rectilinear motion of said slide, substantially as and for the purpose specified.

3. In an electric-arc lamp, a carbon-carrier, a reversible rotary motor having two field-magnet helices, and an electro-magnet and an armature thereof provided with suitable contacts and connections whereby the armature of said motor is connected in series with one and in parallel with the other of said helices or in parallel with the former and in series with the latter of said helices, or is disconnected from both, according as the armature of said electro-magnet is moved to a predetermined limit in one direction or in the other direction, or is not moved to such limit,

in combination with mechanism which is adapted to convert the rotary motion of the armature of said motor into rectilinear motion of said carrier, substantially as and for the purpose specified.

4. In an electric-arc lamp, a feeding-rod which is provided with a screw-thread and an engagement-pin, in combination with a carbon-carrier which engages said thread, and to a wheel having a slotted hub which engages said pin, substantially as and for the purposes specified.

5. In an electric-arc lamp, a sliding yoke which has two sleeves joined and held rigidly parallel by an intermediate cross-piece which is insulated from each of said sleeves and is provided with a carbon-holder and with mechanism for engaging a feeding-rod, substantially as and for the purpose specified.

15 6. In an electric-arc lamp, a reversible rotary motor, a feeding-rod which is provided with a screw-thread, intermediate gearing whereby said motor constantly engages said feeding rod, and a lifting-magnet which is applied to said feeding-rod, in combination with a sliding-yoke having two sleeves joined and held rigidly parallel by an intermediate cross-piece which is insulated from each of said sleeves and is provided with a carbon-holder 25 and with a spring-seated engagement-block for engaging said feeding-rod by means of said screw-thread, substantially as and for the purpose specified.

7. In an electric-arc lamp, a four-contact switch whose actuating-magnet is wound with two helices arranged in parallel with each other and with the carbons of the lamp, substantially as and for the purpose specified.

35 8. In an electric-arc lamp, a rotary feeding-rod which is divided into two parts by means of an insulating-joint, in combination with rotating mechanism which engages one of said parts and carbon-carrying mechanism and an electric brush which are in contact 40 with the other of said parts, substantially as and for the purpose specified.

9. In an electric-arc lamp, a pair of carbons, a stationary-carbon-holder, a movable carbon-carrier, a reversible electric motor, a feeding-rod which has a screw-thread engaging said carrier, intermediate gearing whereby said motor engages said rod, a four-contact switch whose actuating-magnet is wound with two helices arranged in parallel with each other 50 and with said carbons, a lifting-magnet, and a switch operated thereby, which opens and closes the circuit-connection of one of said helices, in combination with a lever engaging said feeding-rod and the armature of said lifting-magnet, substantially as and for the purpose specified.

10. In an electric-arc lamp, carbon-carrying mechanism, a reversible electric motor actuating said mechanism, and a three-point

switch having two helices which are located in-separate shunts about the carbons of said lamp, in combination with a main-circuit lifting-magnet provided with circuit-breaking mechanism which is applied to one of said shunts, substantially as and for the purpose specified.

11. In an electric-arc lamp, carbon-moving mechanism, a reversible motor working said mechanism, a three-point switch controlling said motor and having two helices, one of said helices being composed of fine wire and located in a constantly-closed shunt-circuit about the carbons of the lamp, and the other of said helices being composed of coarse wire and located in a shunt-circuit about said carbons, in combination with a lifting-magnet provided with circuit-closing mechanism which is applied to the last-mentioned shunt-circuit, substantially as and for the purpose specified.

15 12. In an electric-arc lamp, a movable carbon-carrier, an electric motor whose field-magnet is excited by two helices in series and whose armature is located in a derived circuit, and gear mechanism engaging said armature and said carrier, in combination with a four-contact switch whose actuating-magnet is wound with two helices severally arranged in parallel with the carbons of the lamp, substantially as and for the purpose specified.

30 13. In an electric-arc lamp, a movable carbon-carrier, a reversible electric motor whose field-magnet helices are arranged in series and whose armature is located in a branch circuit connecting with the field-magnet circuit at a point between said helices, and a three-point switch having two helices which are located in separate shunts about the carbons of the lamp, in combination with a circuit-breaking mechanism which is applied to one of said shunts, substantially as and for the purpose specified.

35 14. In an electric-arc lamp, a movable carbon-carrier, an electric motor whose field-magnet helices are arranged in series and whose armature is located in a branch circuit connecting with the field-magnet circuit at a point between said helices, and a compound switch controlling said motor and having two helices which are located in separately-derived circuits about the carbons of the lamp, in combination with a lifting-magnet and a circuit-breaking mechanism which is applied to one of said derived circuits, substantially as and for the purpose specified.

In testimony whereof I have hereunto set my name in the presence of two witnesses.

RICHARD H. MATHER.
